J. B. LADD

CASTING APPLIANCE

Filed Jan. 5, 1923

*Inventor.
James B. Ladd.*

by Francis J. Chamberlain
his Attorney.

UNITED STATES PATENT OFFICE.

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

CASTING APPLIANCE.

Application filed January 5, 1923. Serial No. 610,743.

To all whom it may concern:

Be it known that I, JAMES B. LADD, a citizen of the United States of America, and resident of Ardmore, in the county of 5 Montgomery, in the State of Pennsylvania, have invented certain new and useful Improvements in Casting Appliances, of which the following is a true and exact description, reference being had to the accompanying 10 drawings, which form a part thereof.

My invention relates to casting appliances especially adapted for use in connection with centrifugal molds and particularly designed for use where a core piece is required, as, for instance, in casting a pipe 15 with a bell mouth. The object of my invention is to provide a core which, in itself and also in connection with appliances to be used therewith, can be made entirely of 20 metal, so as to avoid the use of molding sand which has heretofore been employed to partly or wholly make up such cores.

The nature of my improvements will be best understood as described in connection 25 with the drawings in which—

Figure 1 is a longitudinal section through one end of a centrifugal mold showing my improved appliance as it is used in connection with such molds.

Figure 2 is an enlarged view showing my improved appliance as shown in Fig. 1.

Figure 3 is an end view of the inner end of the core piece.

Figure 4 is a cross sectional view on the 35 line 4—4 of Fig. 1.

Figure 5 is a sectional view showing a modification in the construction of my core piece.

Figure 6 is a cross sectional view on the 40 line 6—6 of Fig. 5, and

Figure 7 is a perspective on an enlarged scale showing the usual mold appliances used in connection with the construction shown in Fig. 5.

A indicates the casing of the molding apparatus. B, the rotatable mold having an enlarged bell forming section indicated at B', a peripheral flange indicated at B² and a projecting ring indicated at B³ and formed 50 with wedge holes, as indicated in Fig. 1. The mold is also formed with a conical seat B⁴ for the core ring. C is the core ring shown in position on the seat B⁴ and held in position by wedges indicated at D. E, E, indicate packing between the flange B² of the

rotatable mold and the casing A, said casing constituting, as indicated, a water jacket for cooling the mold.

F, Figs. 1, 2, 3 and 4, is an annular metallic core piece, the inner end of which is divided into tongues F' by longitudinally running slots indicated at F². The ends of the tongues F' are preferably chamfered, as indicated at F³. G is an annular ring secured on the core F, as indicated, and having an outwardly projecting portion G' surrounding the end in contact with the outer portion of the ring F and divided into tongues G' by longitudinally running slots G². H is a thin metal shell preferably of 60 sheet metal and having the conformation which it is desired shall be imparted to the bell mouth of the casting and, as shown, the ends H' and H² of this shell rest upon the inner ends of the tongues F' and the 65 outer ends of the tongues G'. I indicates the casting and J the end of a runner through which molten iron is introduced into the mold.

In the modification illustrated in Figs. 80 5, 6 and 7, the annular core here indicated at f is divided into tongues f' by slots f² running clear back to the core ring C and the outer portions of these tongues are further divided from each other by an annular slot f³ forming an additional set of tongues indicated at f⁴. h indicates a thin metal shell having the conformation of the bead to be formed in the bell mouth of the casting, the rest of the bell mouth being 85 90 cast directly against the tongues f' and f⁴ of the core ring.

In operation the annular slotted core F is placed in position on the core ring C and the thin shell H is placed in position on the 95 tongues of the core, as indicated in Fig. 1; the parts being thus assembled the core ring supporting the core is inserted in the mold and locked in position as by the wedges D. The metal is then run into the mold, filling 100 the space around the core as indicated in Fig. 1 and practically forming a union with the shell H. In solidifying and cooling the metal of the casting, of course, contracts but the pressure due to contraction comes 105 upon the slotted tongues F' and G' which are sufficiently flexible to contract under this pressure and prevent any disruptive effect upon the casting. The casting being complete the casting is withdrawn from the 110

mold and the core withdrawn from the casting leaving the shell H in use as a part of the casting.

In the construction shown in Fig. 5, the 5 slotted metallic core comes in direct contact with the castings except where the shell h is used, if such a shell is used, and it is only necessary where a depression is to be formed in the bell. Obviously, the slotted annular 10 core is capable of contracting under the pressure of the contracting casting so as to relieve the casting of disruptive strains and, at the same time, permit the extraction of the slotted core from the casting after it 15 has solidified.

In any case where the slotted metal core comes in direct contact with the melted metal the slots must be so narrow that the metal will not run into them, this however 20 does not involve any difficulty since the metal core is a good conductor and the melted metal rapidly chills in contact with it. Where the shell pattern used covers the slotted core the slots may, of course, be made 25 broader.

Having now described my invention, what I claim as new and desire to secure by Letters Patent, is:

1. A casting appliance consisting of a 30 metal core piece in combination with means for forming a depression in the casting consisting of a thin metal shell supported on the metal core piece.

2. A casting appliance consisting of a 35 metal core piece made contractible under the pressure of a shrinking casting by slots in combination with means for forming a depression in the casting consisting of a thin metal shell supported on contractible portions of the core piece.

3. A casting appliance consisting of a 40 metal core piece made contractible under the pressure of a shrinking casting by slots in combination with a thin metal shell having the conformation of the inside of the

casting to be made surrounding the core piece and supported on yielding portions thereof.

4. A casting appliance consisting of a 50 metal core piece made contractible under the pressure of a shrinking casting by slots in combination with a thin metal shell having the conformation of the inside of the casting to be made surrounding and covering the face of the core piece and supported on 55 yielding portions thereof.

5. A casting appliance consisting of an 60 annular metallic core piece having an annular ring spaced from its main body enclosing its outer active portion, the inner portion of the main core piece and the outer portion of the ring being divided into elastic tongues by slots to make the core contractible.

6. A casting appliance consisting of an 65 annular metallic core piece having an annular ring spaced from its main body enclosing its outer active portion, the inner portion of the main core piece and the outer portion of the ring being divided into elastic tongues by slots to make the core contractible, in combination with a thin metal shell supported on yielding portions of the 70 slotted core piece.

7. A casting appliance consisting of an 75 annular metallic core piece having an annular ring spaced from its main body enclosing its outer active portion, the inner portion of the main core piece and the outer portion of the ring being divided into elastic tongues 80 by slots to make the core contractible, in combination with a thin metal shell having the conformation of the inside of the casting to be made enclosing and covering the core piece and supported on the outer ends 85 of the tongues of the main core piece and the inner ends of the tongues of the annular slotted ring.

JAMES B. LADD.
